UNITED STATES PATENT OFFICE.

PATRICK J. WALSH, OF WORCESTER, MASSACHUSETTS.

CONVEYER.

Application filed October 19, 1921. Serial No. 508,667.

To all whom it may concern:

Be it known that I, PATRICK J. WALSH, a citizen of the United States of America, and a resident of Worcester, in the county of

5 Worcester and Commonwealth of Massachusetts, have invented certain new and useful Improvements in Conveyers, of which the following is a specification.

This invention relates to conveying mechanism and more particularly to a type suitable for use in rolling mills, to receive metal rods, bars and the like and convey them to a distant point for the purpose of cooling or assembling for further distribution.

10 15 In this type of conveyer it has been the practice to receive the rods, as they came from the mill, in a trough-like structure which was provided with a series of rolls whose peripheries projected through the floor of the trough. These rolls were conical in shape and were driven in the proper direction to give longitudinal advancement to the rods until such time as the rods had reached the required location, when the axes 20 25 of the rolls were swung to thereby cause a broadside movement or travel to the rods, which carried them into operative position with other devices by which they were removed from the trough.

30 35 Heretofore these rolls were driven in series by an endless belt or by a motor directly connected to each roll. The former of these methods was very unsatisfactory, due to the frequent breaking of the rope or belt drive which occasioned the shutting down of the conveyer for repairs, and stretching of the rope, causing slippage and lack of uniform drive. The latter or motor drive is a costly one to install and as each individual 40 45 motor requires frequent attention it will be readily seen that the first cost had to be followed up by the additional one for labor, together with the fact that the motors as used are induction motors and a uniformity of speed for a series is difficult to maintain. Obviously, the possibility of breakdown increased with the number of motors used.

An object of the present invention is to dispense with both of the above methods, 50 and instead produce a drive that is capable of driving a series of rolls in a positive and uniform manner and speed.

A further object is to so arrange the positive drive means that the rolls may be 55 swung in such manner as to cause a change of direction of travel of the bars from a

longitudinal to a lateral direction, the nature of the drive means aiding in the swinging movement.

Another object of the invention is to produce a drive means having all the virtues above described, with the additional advantage of simple structure, which when once installed will last indefinitely, and which requires but little attention in the upkeep 60 65 thereof, such, for instance, as occasional oiling.

Durability of conveyers of this type is especially essential in mills having great production, as it will be readily seen that a 70 breakdown of a conveyer means that the mill with which it cooperates must shut down, thus curtailing its output, while the operations at the discharging point of the conveyer must cease for lack of material. 75

Obviously, simplicity and durability are essentials for the best results and it is an object of this invention to provide these essentials.

The invention further consists in certain 80 novel features of construction and arrangement of parts which will be readily understood from a description of the drawings and the claims hereinafter given.

Of the drawings:

Figure 1 represents in top plan a sufficient portion of a conveyer to enable the invention to be understood. The rolls are shown in the figure as having been swung to effect discharge of a rod or bar to other handling 90 devices not forming a part of this invention.

Figure 2 an enlarged view of one of the rolls shown in Figure 1.

Figure 3 a view looking in the direction 95 of the arrows A—A Figures 2 and 4, showing the roll and certain other parts in section.

Figure 4 a view looking in the direction of arrow B, Figure 3.

Figure 5 a top plan view similar to Figure 2 but showing the roll in normal position to cause longitudinal advancement to the rod or bar.

Like characters designate like parts 105 throughout the several figures of the drawings.

Referring to the drawings:

The herein shown conveyer is of a type used at the present time, wherein the material to be conveyed may be a rod or bar of considerable length and weight and

which is presented to the conveyer by the feed rolls of a mill. In this instance the material is fed to the conveyer in the direction of the arrow C, (see Figure 1) and 5 preferably the surface speed of the rolls approximates that of the fed material.

The purpose of the conveyer is to relieve the mill of its finished product and convey it to some distant point to cool or to be assembled for further distribution. To accomplish the above, a trough-like runway 10 is provided, having a side wall 11 at the left 10 is provided, having a side wall 11 at the left side thereof and cutaway portions 12 and 13, the former to accommodate the conical 15 rolls 14 and the latter to accommodate the elevator members 15 to be later briefly described.

The runway 10 will be positioned to suit the use thereof and will be supported in any 20 well-known or suitable manner.

A channel iron or girder 16 forming part of the supporting structure for the trough 10 has at intervals fast thereto brackets 17 which constitute supporting members for the 25 rolls 14 and the drive means therefor.

Viewing Figures 3 and 4 the bracket is shown as provided with bearings 18 and 19 for a vertical shaft 20 which also serves as a pivotal support for the roll carrying 30 bracket 21 in conjunction with said bearing 18. The said bracket 21 having a cylindrical depending portion 22 revolvably mounted in bearing 18 and resting therein upon an adjustable step 23 composed of a screw 35 threaded bolt 24 having a running fit with the shaft 20 and vertically adjustable in the bearing 18 by means of the screw threads therein. A bushing 25 is interposed between the shaft 20 and the portion 22 as 40 is usual in such instances.

The shaft 20 has fast thereto at the upper end thereof a bevel gear 26 meshing with 45 bevel gear 27 fast on a shaft 28 to which is also secured the roll 14. The said shaft 28 being provided with a bushing 29 and revolvably held in a bearing 30 of the bracket 21 by a nut 31.

At the lower end of said shaft 20 a bevel gear 35 is mounted, the shaft being squared 50 as at 36 to correspond with the broached hole 37 in the gear 35 and hub thereof. The said hub 38 is rotatably held in the bearing 19 in such manner that adjustment of the bracket 21 and consequently the shaft 20 vertically may take place, the squared portion 36 of shaft 20 while forming a driving means for said gear 35 is capable of sliding therein to compensate for the adjustment above referred to.

60 At the lower end of the bracket 17 a bearing is provided for the main drive shaft 40, in fact each of the brackets is so provided or as many thereof as will consistently support the said shaft.

The drawing Figure 1 shows but two drive 65 rolls 14 but it will be understood that the number may be increased the desired amount. Each drive roll will be mounted and driven in the manner above described, each receiving its power from the shaft 40 70 to which bevel gears 41 are fast, which mesh with the gears 35 one of each of which is shown.

From the foregoing it will be readily seen 75 that the power of shaft 40 is transmitted by gear 41 to gear 35, shaft 20, gear 26 to gear 27 and consequently drives rolls 14. This arrangement is a thoroughly practical 80 one because of its simplicity, reliability and durability.

The service for which this conveyer is designed is such that it is necessary to so arrange the rolls 14 that they may first serve to advance the rods longitudinally to the approximate required position and thereafter cause the said rods to be moved laterally to be discharged.

For this purpose the roll carrying bracket 21 is pivotally mounted about the shaft 20.

Referring to Figures 2, 4 and 5 particularly, the said bracket 21 has outwardly extended therefrom an arm 45 having a truck 46 pivotally mounted thereon. Coacting with said truck is a cam 47 fast with and between the shiftable bar 48 which in turn 95 find suitable guide means in a gutter-like way 49 secured to the girder 16.

The bar 48 is preferably under manual control as regards the time of shift but the actual movement thereof may be effected 100 by any well-known or suitable means.

An arm 50 also extending from said bracket 21 has spring connection with a stationary strut 51, the tension of the spring 52 being adjustable by means of the bolt 105 53 and nut 54.

During the longitudinal advancement of the rods the rolls 14 will assume positions as indicated in Figure 5 wherein the roll 46 is resting on the high part of cam 47 110 and held snugly thereto by the spring 52. This position of rolls 14 advances the rods longitudinally and slightly to the left till they meet the wall 11 which ensures the proper longitudinal alignment of the rods 115 preparatory to the discharge thereof.

When, however, the rods approximately reach the proper discharging point the bars 48 will be shifted to assume the position shown in Figure 2, whereupon the rotation 120 of the rolls 14 will cause lateral movement to the rods, which will bring them into a position to be eventually raised by the elevators 15 and subsequently disposed of as desired.

Shifting the said bars 48 to bring the lower part of cam 47 opposite the truck 46 allows springs 52 to swing the brackets 21

in the direction of arrow D, Figure 5 until said brackets and rolls 14 assume the position seen in Figure 2. The amount of swing given to the brackets may be regulated by 5 the inclines of the cams or the amount of shift of the bars 48.

During longitudinal advancement of the rods the axes X—X of the rolls will preferably assume a slight angular position 10 relative to a line y—y perpendicular to the wall 11 (see Fig. 5) and when lateral movement is being imparted the axes will assume approximately the position shown in Figure 2.

15 The rotation of gears 26 is in a convenient direction to assist the springs 52 in swinging the brackets 21 from the position shown in Figure 5 to that shown in Figure 2, such aid being material, as the rods are of considerable weight and naturally resist the swinging movement of the rolls.

Since the invention resides in the means for driving the rolls 14 it has not been deemed necessary to enter into great detail as to the structure generally or to the apparatus which may act in conjunction with it, as it is obvious that changes might be made in the construction and arrangement of parts without departing from the 30 spirit and scope of the invention.

Having described the invention I claim:

1. In a device of the class described, a series of rotatable feed rolls; bearings for 35 said rolls each of which is rotatable about an axis; a main drive shaft; and a gear drive intermediate each feed roll and said main shaft adapted to drive said rolls irrespec- tive of the angular position thereof.

2. In a device of the class described, a series of rotatable feed rolls; bearings for 40 said rolls each of which is rotatable about a vertical axis; a main drive shaft; and a gear drive intermediate each feed roll and said main shaft adapted to drive said rolls irrespec- 45 tive of the angular position of said rolls.

3. In a device of the class described, a plurality of revoluble feed rolls; bearings for 50 said rolls adapted to be rotated about vertical shafts; a plurality of vertical shafts; gears fast on said shafts; a gear for each roll in driving connection therewith, each in mesh with one of said fast gears; a main shaft; gears on said main shaft adapted to 55 mesh with a like gear on each of said verti-

cal shafts; and means to rotate said bearings about said vertical shafts.

4. In a device of the class described, a plurality of revoluble feed rolls; bearings for 60 said rolls adapted to be rotated about vertical shafts; a plurality of vertical shafts; a gear fast on each of said shafts; a gear for each roll in driving connection therewith, each in mesh with one of said fast gears; a main shaft; gears on said main shaft adapt- 65 ed to mesh with like gears on each of said vertical shafts; and means to rotate said bearings about said vertical shafts.

5. In a device of the class described, a plurality of revoluble conical feed rolls; 70 bearings for said rolls adapted to be swung about vertical shafts; a plurality of gears each having driving connection with one of said rolls; a plurality of vertical shafts, each having a gear fast thereon to mesh with said 75 rolls driving gear; a bracket to sustain each of said vertical shafts; a gear for each of said vertical shafts having a sliding, driving connection therewith; means to vertically adjust each bearing and the shaft about 80 which it is rotatable, simultaneously; a main drive shaft; and gears on said main shaft, each of which is in mesh with one of said slidably connected gears.

6. In a device of the class described, a series of rotatable feed rolls; means to positively drive said rolls at a uniform speed from a common source, said means including a gear train; and means to change the angular position of said rolls relatively to the 90 material fed while the feed rolls are being driven.

7. In a device of the class described, a series of rotatable feed rolls the axes of which are angularly arranged to a horizontal; bear- 95 ings for said rolls adapted to revolve about vertical axes; a gear fast with each of said rolls rotatable about the axes of said rolls and revoluble about said vertical axes; a vertical shaft for each roll rotatable about the 100 said vertical axes; a gear on each of said shafts in mesh with said roll gear and about which said roll gear may revolve while still in mesh; means to drive said shafts; and means to cause said bearings and consequently said 105 rolls to revolve about said axes.

Signed by me at Boston, Mass., this 15th day of October, 1921.

PATRICK J. WALSH.
